OLIVER SEIFFERLE, OF PORTLAND, OREGON, ASSIGNOR TO J. C. DENNIS CO.

CARBURETOR

Application filed June 24, 1929. Serial No. 373,309.

The carburetors used with the present day automobile engine, which is adapted for a wide range of working speeds, a low idling speed and rapid acceleration are, in my opinion, inadequate, since the said high range of speeds requires a widely varying volume of vaporized fuel ranging from very little for the idling speed to a relatively great volume for the higher speeds, and as ancillary condition, the suction created by the intake strokes of the pistons of these engines also varies greatly with the result that larger volumes of fuel are required to be drawn into the engine at some of the speeds than the carburetor can supply and at other speeds more is drawn into the engine cylinders than is required for efficient combustion.

Many of the present day carburetors, being provided with only one fuel inlet of fixed capacity, cannot supply a properly intermixed volume of fuel and of air to meet all the varied running conditions of the engine.

Therefore, I have found it desirable to provide a series of fuel inlets or jets adapted to be brought into service in succession as the throttle is opened to increase the speed of the engine, whereby the capacity of the carburetor may be varied to meet the varying demands of the engine for greater or less volumes of fuel.

Furthermore, in the operation of the engine as it first commences to pull its load, the suction created by the intake stroke of the pistons which draws the fuel and air vaporized and intermixed in the carburetor into the engine cylinders, is less than when it has gained momentum and the pistons are operating more rapidly on the same relative volume of fuel; the results of which are that the engine is starved for fuel at first and then as the suction increases, the fuel is picked up in unvaporized quantities and delivered to the cylinders "raw", causing them to be "flooded" and the engine to run unevenly and discharge volumes of unburned fuel commonly known as "smoke", which is objectionable as to odor and more or less poisonous.

Hence I have found it desirable to pro-

vide a predetermined auxiliary reservoir of fuel for and adjacent to each of the said fuel jets so that when the engine is first accelerated and the suction is relatively weak the fuel may be easily picked up off the jets and vaporized in the carburetor, until the engine has gained in momentum and the suction becomes strong enough to efficiently draw the fuel directly from the main reservoir of the carburetor.

I have further found that with the carburetors as at present constructed when the engine is decelerated and the throttle is in the idling position, at which time the engine is operating due to its momentum, much faster than at the normal idling speed, that the suction is so strong as not only to pick up raw gasoline off the fuel jet with the result that more fuel is drawn into the cylinder than is required and part of which is unburned and exhausted in the form of the said objectionable fumes, but also the suction so created is so strong as to draw lubricating oil from the crank case past the pistons and into cylinders where it is intermixed with the said partly burned fuel and increases the said objectionable odor as well as being wasteful of the said lubricating oil.

Such fumes and odors are found to be especially noticeable on commerical busses, as well as other motor vehicles, which are commonly used for urban transportation where frequent stops are made at each street crossing to take on or let off passengers.

Therefore, I have also found it desirable to provide an independent fuel and air inlet for the idling position of the carburetor and to provide an auxiliary air inlet from the atmosphere to said fuel and air inlet and means operated by increased suction through the said air and fuel inlet when the engine is decelerated and the suction is very strong, to open the said auxiliary air inlet and shut off the fuel inlet until the speed of the engine has decreased to the normal idling speed and the suction has fallen correspondingly, thus admitting additional air to the cylinders while it is decelerating to prevent lubricating oil from being drawn from the crank case and by shutting off the

fuel inlet to prevent raw unvaporized fuel from being drawn into the cylinder from the carburetor with the said further objectionable results.

5 The principal object of my invention is to provide an improved carburetor for internal combustion engines, specifically automobile engines, adapted to supply a proper mixture of vaporized fuel and air to the cylinders of the engine, under all running conditions, as of starting, idling acceleration and deceleration, whereby greater economy of fuel and a smoother running engine are attained than with the carburetors in present use.

10 A still further object of my invention is to provide a carburetor adapted to eliminate the above mentioned objectionable and poisonous fumes from being exhausted from the engine which are especially predominant during rapid acceleration and deceleration of the engine as before mentioned.

15 A still further object of my invention is to provide a carburetor adapted to automatically admit additional volumes of air through an independent supplementary air inlet into the throttle valve chamber of the carburetor whereby a sufficient volume of air will always be intermixed with the vaporized fuel to insure complete and rapid combustion and the efficient and economical functioning of the engine.

20 These objects and other incidental features of my invention, the details of construction and mode of operation are hereinafter fully described with reference to the accompanying drawings.

In the drawings:

25 Fig. 1 shows diagrammatically a side elevation of my carburetor;

30 Fig. 2 shows an enlarged section taken on the lines 2—2 of Fig. 1, and of Fig. 6 and illustrates the auxiliary wells of each fuel jet;

35 Fig. 3 shows an inverted fragmentary enlarged view partly in section taken looking from underneath my carburetor as shown in Fig. 1, with the inlet housing removed and illustrates the passageways leading from the said wells to the fuel jets;

40 Fig. 4 shows an enlarged section taken on the lines 4—4 of Figs. 1 and 6;

45 Fig. 5 shows a section of my carburetor taken on the line 5—5 of Fig. 6;

50 Fig. 6 shows an enlarged vertical section taken on the fragmentary line 6—6 of Fig. 3 and illustrates in greater detail the relative arrangement of the parts;

55 Fig. 7 shows a section taken on the line 7—7 of Fig. 6.

60 Referring now to the drawings and particularly to Figs. 1 and 6, my carburetor comprises a housing *a* including a main air inlet *b* and outlet *c*, the latter adapted to be connected in the usual manner to the intake

manifold of an automobile engine, not shown. The said housing comprises a main reservoir *g* in which is provided the usual float valve *h*, an air mixing chamber *i* connected with the air inlet *b*, a throttle valve chamber *j* 70 and a supplementary air inlet valve chamber *k*.

65 A plurality of ducts *p*, *p'*, *p2*, *p3* leads from the bottom of the main reservoir *g*, Figs. 2 and 3 to the bottom of cylindrical 75 wells *q*, *q'*, *q2*, *q3*. Regulating needle valves *r* are threaded in vertical recesses in the said ducts *p*, *p'*, *p2*, *p3* and adapted to regulate the flow of fuel therethrough from the reservoir *g*.

70 Adjustable covers *d* are threaded in the top of each well by which their capacity may be regulated and air ducts *e* are provided in each cover to permit the free passage of fuel into and from the said wells.

75 A duct *t* leads from the well *q* and opens into a Venturi tube 2 located in the air mixing chamber *i*. The Venturi tube 2 is connected at its upper end through an accelerator passageway 2a with the throttle valve chamber *j*. Similarly, ducts *t'* and *t3* lead from the wells *q'*, *q3* to Venturi tubes 3 and 4 which open through accelerator passageways 3a and 4a respectively arranged adjacent to and in successive order to the passageway 2a into the said throttle valve chamber *j*. The passageway 4a being of relatively greater size than the passageway 3a. Two conduits *t4* and *t5* lead from the well *q2* and open into Venturi tubes 5, 5a.

80 The Venturi tubes 5, 5a are connected to a still larger accelerator passageway 5b opening into the throttle valve chamber *j* adjacent to the passageway 4a.

85 By this construction fuel from the main reservoir *g* will flow through the ducts *p*, *p'*, *p2*, *p3* to their respective wells and through the ducts *t*, *t'* and *t4*, to their respective Venturi tubes until the level of the fuel reservoir *g* is reached.

90 Thus the wells hold an auxiliary supply of fuel adjacent to the Venturi tubes which may be easily picked up and vaporized and a graduated supply of vaporized fuel is provided to meet all the requirements of the motor under its varied running conditions as each accelerator passageway is brought successively into service as hereinafter further described.

95 Another duct 11 is connected to the well *q3* leading through a port 11a into an idling passageway 12 opening into the throttle valve chamber *j* at the side of the accelerator passageway 5b. An air passageway 8 is provided in the outer end of the idling passageway 12 regulated by a screw 8a.

100 The end of the passageway 12 adjacent to the port 11a is enlarged somewhat forming a valve chamber 9 and a piston valve 16 is 130

provided therein, carrying a port 18 in its skirt which is adapted in one position to register with an auxiliary air passageway 20 in the wall of the valve chamber 9.

5 A needle valve 13 is loosely carried in a web of the lower end of the piston valve 16 and is adapted to seat in the port 11a. The upper end of the needle valve 13 is provided with a nut 13b and is held normally extended from the piston valve 16 by a spring 13a secured to the lower end of the needle valve, as at 13c, and bearing against the web of the piston valve, so that when the piston valve is moved downward due to the action of an excessive degree of suction in the idling passageway, the port 11a will first be closed by the needle valve and then as the piston valve continues to move downward on the needle valve, the passageway 20 will be opened and 15 permit auxiliary volumes of air to be admitted to relieve the excessive suction.

The upper end of the stem 16a of the piston valve 16 projects through the housing and is provided with an expansion spring 18 bearing against the exterior of the housing at 25 one end and against a nut 18a carried by the stem at the other to normally hold the passageway 20 closed and the port 11a open. Relief ports 18b are provided in the housing 30 above the said piston valve 16, see Fig. 6.

Within the throttle valve chamber *j* is provided the throttle valve 25 comprising a shaft 25a journaled in the walls of the chamber as at 25b and spaced circular sides 25c, 25 the latter carrying webs 26 and 27 arranged at approximately opposite sides of the valve. The web 26 is of such width and is so arranged as to close the accelerator passageways 2a, 3a, 4a and 5b when the idling passageway 12 is opened, see Fig. 6, and when 40 the valve member is rotated in an anti-clockwise direction by means of a lever 25d and suitable operative connections, not shown, to close the idling passageway 16 and open the accelerator passageways 2a, 3a, 4a and 5b successively.

50 Stops 25e are provided on the exterior of the throttle valve chamber walls at each side of the lever 25d to limit its movement to closing and opening the several passageways leading into the said chamber.

A supplementary air inlet 30 is provided in the throttle valve housing approximately opposite the accelerator and idling passageways 55 and is controlled by the web 27 so that the supplementary air inlet is closed when the idling passageway 12 is open, and is opened simultaneously as the idling passageway is closed and the accelerator passageways are 60 opened successively.

65 A valve 31 is located in the said supplementary valve chamber *k* adapted to be actuated when the supplementary air inlet in the throttle valve chamber *j* is open, by a predeter-

mined degree of suction in the said throttle valve chamber.

The valve 31 is carried on the upper end of a valve stem 32 and is adapted to be normally seated on the inner side of a valve port 70 33 which opens to the atmosphere. The stem 32 projects above the said valve 31 and is guided in a frame 34 integral with the housing of the valve chamber. An expansion spring 35 is mounted on the stem 32 above 75 the frame 34 and bears against and is held in place by a nut 32a to normally hold the valve 31 closed. A bell crank lever 36 is pivotally carried by the frame 34 the end of which engages with a loose washer 35a arranged at the lower end of the spring 35 and serves as a manual means for restraining the operation of the valve 30, the other end of the lever being connected by suitable means, not shown, within the driver's compartment 80 of the automobile.

The lower end of the stem 32 is secured in a tubular member 40 by a set screw 32b and extends through the lower wall of the chamber *k* into a dash pot 41 and carries on 90 its lower end a flange 42. A pin 43 is secured in the lower end of the tubular member 40 by a screw 43a and projects through a plunger 44 loosely mounted thereon. The pin 43 is provided on its lower end with an expansion spring 45 bearing against the underside of the plunger 44 at one end and against a nut 46 on the end of the pin at the other. A by-pass 47 is provided in the wall 95 of the dash-pot 41 connecting the space in the dash-pot above the plunger 44 with the space below, and regulating screw 47a is threaded into the said by-pass. Ports 44a are provided in the plunger adapted to be closed by the flange 42 when in contact therewith.

100 The dash-pot is provided with a suitable oil adapted to resist the downward movement of the plunger 44 since it can only escape through the relatively smaller by-pass 47.

110 By this construction means are provided whereby when an insufficient supply of air is being supplied to the engine cylinders through the inlet *c* and the suction in the intake manifold is excessive, the valve 31 will be drawn downward opening the port 33 and admitting additional volumes of air to relieve the said excessive suction. The port 33 will remain open until the said suction falls to such a point as to permit the spring 35 to close the valve 31. The function of the dash-pot 41 is to prevent sudden and rapid opening of the valve 31, but since the flange 42 only bears against the plunger 44, the spring 35 can quickly close the said valve 31.

115 120 125 Special baffles 50 are provided in the outlet *c* to insure the thorough intermixture of the vaporized fuel and the air admitted from the supplementary passageway 30; and a choke valve 51 of the usual form is provided in the air inlet *b* which though rarely needed 130

with my carburetor may be required under extremely severe starting conditions of the motor, the latter being operable by a lever 51 and suitable operative connections not shown.

Now, in the operation of my carburetor assume that the engine has been started and is idling. The throttle valve 25 will be in the position shown in Fig. 6 with the idling 10 passageway 12 only open, the passageway 30, of course, being closed. Air is then being drawn by the suction created by the pistons from the air passageway 8 through the idling passageway 12 and as it passes over the port 15 11a it draws up and vaporizes fuel from the duct 11, thus supplying a proper idling mixture.

However, assume that the engine has been accelerated while pulling its load, and then 20 the throttle valve is closed, that is, returned to its initial position, then the engine while decelerating is operating faster than its normal idling speed and the suction through the idling passageway 12 is very great, tending 25 to draw raw fuel from the duct 11 and at the same time to suck lubricating oil from the crank case past the pistons causing the heretofore mentioned objectionable fumes and waste of both lubricating oil and fuel.

In my carburetor however this excessive 30 suction draws the piston valve 16 and the needle valve 13 down until first the port 11a is closed and the fuel is shut off and then as it moves further down opens the auxiliary 35 air passageway 20 and admits additional air to relieve the said suction, thus preventing the said undesirable results.

Further, when the engine is first accelerated, it is operating slowly in proportion to the 40 volume of fuel being supplied and the suction is relatively weak, so that by providing auxiliary volumes of fuel sufficient to supply the engine during such first period, adjacent to the Venturi tubes, the fuel may be easily 45 picked up and vaporized, and then when the engine has gained in momentum and the suction is stronger, the engine will then be capable of drawing fuel from the main reservoir, the fuel in the wells being of such pre- 50 determined quantity as to have been exhausted during the first part of the acceleration. Further as the throttle valve is opened wider, and the engine correspondingly accelerated and each accelerator passageway is brought 55 into service this auxiliary supply of fuel is similarly used and for the same purpose, thus providing a smooth running engine and preventing it from being starved at first causing fuel to be jerked into the carburetor in its raw state, which is undesirable and causes the 60 engine to run unevenly.

I have also found that with my carburetor, not only have I provided means for eliminating fumes due to partially burned fuel and 65 lubricating oil, but I have reduced the amount

of dangerous carbon monoxide to a negligible point, which is ordinarily a product of combustion of internal combustion engines since with the present carburetor the engine is nearly always operated on an insufficient supply of air, causing the formation of the dangerous carbon monoxide as a final combustion product instead of the harmless carbon dioxide which is the natural final product, but which cannot form because of the lack of sufficient air to provide the additional molecule of oxygen for changing the monoxide to the dioxide.

I claim:

1. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi-tubes, respectively with the throttle valve chamber, ducts leading from the said wells and opening into the said Venturi-tubes respectively, and said manually operated throttle valve adapted to open one or more of the ports of said accelerator passageways successively.

2. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi-tubes, respectively with the throttle valve chamber, ducts leading from the said wells and opening into the said Venturi-tubes respectively, a supplementary idler passageway from one of said wells to said throttle valve chamber, a valve controlling the passage of fuel into said idler passageway, and said manually operated throttle valve adapted to close the port of said idler passageway when operated to open one or more of the ports of said accelerator passageways successively.

3. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi tubes, respectively with the throttle valve chamber, ducts leading from the said wells and opening into the said Ven-

5 turi tubes respectively, a supplementary idler passageway from one of said wells to said throttle valve chamber, a valve controlling the passage of fuel into said idler passageway, an air inlet in said idler passageway, and said manually operated throttle valve adapted to close the port of said idler passageway when operated to open one or more of the ports of said accelerator passageways successively.

10 4. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series 15 of accelerator passageways connecting the said Venturi tubes, respectively with the throttle valve chamber, ducts leading from the said wells and opening into the said Venturi tubes respectively, a supplementary idler passageway from one of said wells to said throttle valve chamber, a valve controlling the passage of fuel into said idler passageway, an air inlet and an auxiliary valve controlled air inlet in said idler passageway, the valve controlling the passage 20 of fuel into said idler passageway and the valve controlling the auxiliary air inlet of the latter being connected so as to close said fuel passageway before the opening of said auxiliary air inlet, a supplemental air inlet into said throttle valve chamber, a valve responsive to suction controlling said supplemental air inlet, said manually operated throttle valve adapted to close the port of said idler passageway when operated to open 25 one or more of the ports of said accelerator passageways successively and simultaneously to open said supplemental air inlet, and vice versa.

30 5. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi tubes, respectively with the throttle valve chamber, ducts leading from the said wells and opening into the said Venturi tubes respectively, a supplemental air inlet for said throttle valve chamber, a valve responsive to suction controlling the said supplemental air inlet, 35 means in combination with said valve causing the latter to open slowly when actuated by said suction, and other means adapted to rapidly close the said valve when the suction is discontinued.

40 6. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi tubes, respectively with the throttle valve chamber, ducts leading from the said wells and opening into the said Venturi tubes respectively, a supplemental air inlet into said throttle valve chamber, a valve responsive to suction controlling said supplemental air inlet, and said manually operated throttle valve adapted to open one or more of the ports of said accelerator passageways successively, and simultaneously to open said supplemental air inlet, and vice versa.

45 7. A carburetor comprising a housing, a main fuel reservoir and a control valve therefor, a manually operated throttle valve, a series of fuel wells, air inlets therefor, ducts connecting said wells with said reservoir reg-

ulating valves in each of said ducts, an air inlet in said housing arranged between said reservoir and the chamber of said throttle valve, a series of Venturi tubes located in said air inlet, a series of accelerator passageways 50 connecting the said Venturi tubes, respectively with the throttle valve chamber, ducts leading from the said wells and opening into the said Venturi tubes respectively, a supplementary idler passageway from one of said wells to said throttle valve chamber, a valve controlling the passage of fuel into said idler passageway, an air inlet and an auxiliary valve controlled air inlet in said idler passageway, the valve controlling the passage 55 of fuel into said idler passageway and the valve controlling the auxiliary air inlet of the latter being connected so as to close said fuel passageway before the opening of said auxiliary air inlet, a supplemental air inlet into said throttle valve chamber, a valve responsive to suction controlling said supplemental air inlet, said manually operated throttle valve adapted to close the port of said idler passageway when operated to open 60 one or more of the ports of said accelerator passageways successively and simultaneously to open said supplemental air inlet, and vice versa.

65 8. A carburetor comprising a housing, a main fuel reservoir and a control valve therefor, a manually operated throttle valve, a series of fuel wells, air inlets therefor, ducts connecting said wells with said reservoir, an air inlet in said housing arranged between said reservoir and the chamber of said throttle valve, a series of Venturi tubes located in said air inlet, a series of accelerator passageways connecting the said Venturi tubes, respectively with the throttle valve chamber, 70 ducts leading from the said wells and opening into the said Venturi tubes respectively, a supplemental air inlet for said throttle valve chamber, a valve responsive to suction controlling the said supplemental air inlet, 75 means in combination with said valve causing the latter to open slowly when actuated by said suction, and other means adapted to rapidly close the said valve when the suction is discontinued.

9. In a carburetor, in combination with the throttle valve and the float valve chamber, a series of independent accelerator fuel feeds of progressively larger capacity and an idler fuel feed connecting said float valve chamber with said throttle valve, said throttle valve adapted when operated to close said idler feed and to open one or more of said accelerator feeds successively and vice versa.

10. In a carburetor in combination with the throttle valve and the float valve chamber, a series of independent accelerator fuel feeds and an idler fuel feed connecting said float valve chamber with said throttle valve, a valve responsive to suction controlling said

- idler fuel feed, said throttle valve adapted when operated to close said idler feed and to open one or more of said accelerator feeds successively and vice versa,
5 whereby when the suction through said idler feed rises above a predetermined point, said idler feed valve will be actuated to proportionately reduce the flow of fuel therethrough.
10. In a carburetor in combination with the throttle valve and the float valve chamber, a series of independent accelerator fuel feeds and an idler fuel feed connecting said float valve chamber with said throttle valve,
15 a valve responsive to suction controlling said idler fuel feed, said throttle valve adapted when operated to close said idler feed and to open one or more of said accelerator feeds successively and vice versa,
20 an auxiliary air inlet for said idler feed and a control valve therefor, said valve controlling the idler fuel feed and said valve controlling the auxiliary inlet connected together, whereby when the suction through
25 said idler feed rises above a predetermined point, said auxiliary inlet will be opened to proportionately reduce the force of said suction and simultaneously said idler feed valve will be actuated to proportionately reduce
30 the flow of fuel therethrough.
11. In a carburetor in combination with the throttle valve and the float valve chamber, a series of independent accelerator fuel feeds of progressively larger capacity and an idler fuel feed connecting said float valve chamber with said throttle valve, a valve responsive to suction controlling said idler fuel feed, said throttle valve adapted when operated to close said idler feed and to open one
35 or more of said accelerator feeds successively and vice versa, whereby when the suction through said idler feed rises above a predetermined point, said idler feed valve will be actuated to proportionately reduce the flow of fuel therethrough.
12. In a carburetor in combination with the throttle valve and the float valve chamber, a series of independent accelerator fuel feeds and an idler fuel feed connecting said
40 float valve chamber with said throttle valve, a valve responsive to suction controlling said idler fuel feed, said throttle valve adapted when operated to close said idler feed and to open one or more of said accelerator feeds successively and vice versa, whereby when the suction through said idler feed rises above a predetermined point, said idler feed valve will be actuated to proportionately reduce the flow of fuel therethrough, a supplementary air inlet for said throttle valve chamber, a control therefor responsive to suction.

OLIVER SEIFFERLE.
